SCREEN AND STORM WINDOW FASTENER

Filed June 14, 1939

UNITED STATES PATENT OFFICE

2,225,163

SCREEN AND STORM WINDOW FASTENER

Albert C. Dohrman, River Grove, Ill.

Application June 14, 1939, Serial No. 279,092

1 Claim. (Cl. 292—241)

The present invention relates in general to devices for securing removable sashes to a usual window frame construction and is more specifically concerned with improved fastening devices for securing screens and storm windows to a window frame.

One of the principal objects of the present invention is to provide a fastening device for screens or storm windows for securing them within a window frame from the inside of the building, thereby eliminating the use of ladders or similar means when such fastening devices are operated from the outside only. This improved feature results in the safety of the individual installing such windows and decreases materially the time required in doing such work.

Another object of the invention is to provide a fastening device so placed as to be inaccessible from the outside to give protection thereto from the elements and from outside removal by intruders.

A further object is to provide a fastener having a slot to turnably engage an adjustable locking means to result in a camming effect for tightly drawing the screen or storm window into the well of the window frame when the fastener is turned to a locked position.

Still another object of this invention is to provide a fastener which may be positively locked against accidental disengagement by tightening a screw which engages with the camming slot after the fastener is turned to a locked position. By tightly locking the screen or storm window in place, they are prevented from becoming partially or totally disengaged from the frame well, should the two lower fasteners be disengaged by children or by some accidental means.

A further object of the invention is to provide a window fastener concealed entirely from the outside to give an unbroken and more pleasing outside appearance on the face of the screen or window when secured within the window frame.

A still further object of this invention is to provide a simple fastening device for the purposes described, made preferably of metal but being light and inexpensive and formed by stamping.

Other and further important objects and features of this invention will more fully appear from the following detailed description, taken in connection with the accompanying drawing, which illustrates two embodiments of the invention and in which:

55 Figure 1 is a view in elevation of a window

screen forming one embodiment of my invention as seen from the inside, the window frame being shown in section, the section being taken along the line I—I of Figure 2.

Figure 2 is a broken horizontal section taken substantially along the line II—II of Figure 1 and drawn to an enlarged scale.

Figure 3 is a fragmentary vertical section taken substantially along the line III—III of Figure 2 and drawn to an enlarged scale.

Figure 4 is a view similar to one of the broken halves of Figure 2, showing a modification of my invention.

Figure 5 is a side view in elevation of my fastener device.

Figure 6 is a top view in elevation of the same device.

As shown on the drawing:

In the illustrated embodiments of the invention, there is disclosed in Figure 1 a wall structure 10 in which a window frame 11 is mounted. The frame structure 11 is of the usual construction, as shown in detail in Figure 2, and includes members 12, 13 and 14. An upper window sash 15, comprising a frame 16 and a light 17, is slidably mounted between the parting bead 18 and the projecting inner face 19 of the window frame member 12.

A seat for containing a removable sash, such as a screen 20, which comprises a frame 21, a metal wire screen 22 and a molding 23, is formed by the projecting outside face 24 of the window frame member 12 and the face 25 of the outer casing 26. While the embodiments of my invention, as shown, indicate the use of a removable screen, such other removable sashes as storm windows and the like can be used equally as well.

The device of my invention, a fastener 27, as shown in Figures 3, 5 and 6, has a flat circular base 28 which is operatively mounted on a flat surface and retained in place by a pivot screw 29 passing through a central hole 30. A portion of the base is bent upwardly to form a wall 31 which is carried by and curved in relation to the circular edge of the base. The wall is provided with a slot 32 in spaced relation to the flat base 28. While the preferred embodiment of my invention, as shown in Figure 5, discloses the blind end 33 of the slot 32 to be nearer the base 28 than the open end 34, the device may be operated satisfactorily should the slot be parallel to the base, as will be discussed hereinafter. An integral handle 35 extends upwardly and away from the base 28 and is the means for rotating 55

the device around the pivot screw 29. It has a rounded contour to fit the hand easily.

Figures 2 and 3 disclose one embodiment of my invention, that of mounting the fastener 27 on a removable surface and operatively engaging and securing an adjacent fixed surface. In this embodiment, the fixed surface 36 is the inner free surface of the member 12, which surface faces across the window. The removable surface 37 is the inner face of the frame 21 of a screen or other removable sash which faces into the window and is disposed adjacent and at right angles to the surface 36 when the screen is seated inside the window frame. The fastener 27 is then operatively secured to the surface 37 by the pivot screw 29. A locking screw 38 is then mounted on the surface 36 in a spaced position, opposite and at right angles to the pivot screw 29. The head end of the screw 38 protrudes above the surface 36 at a distance sufficient for the wall 31 and slot 32 to operatively engage with the screw between its head and the surface 36 as the device is turned by hand. When the fastener 27 is rotated by the handle 35 about the pivot 29, the slot 32 may be engaged or disengaged with the locking screw 38.

By embodying a slanting slot 32 relative to the base 28, as shown in Figure 5, the engagement between the slot and the locking screw 38 produces a camming action which draws the screen frame 21 into tight engagement with its window frame seat. The slot 32 may also be spaced in parallel relation to the base 28, but by so doing no camming action is obtained. This can be offset by locking the fastener as described in the following paragraph.

When the fastener 27 is engaged with the locking screw 38, it may be tightly locked against accidental disengagement by screwing the head of the lock screw 38 against the fastener wall 31. Both the pivot 29 and lock 38 are disclosed in the drawing as screw members, but either or both may be any headed member, such as a nail or the like.

The modification of my invention shown in Figure 4 discloses the same members and means for securing a removable sash in a seat formed in a window frame. In this embodiment, the fastener 27 is operatively secured to the fixed surface 36 of the window frame member 12 and engages a locking screw 38 which is mounted on

the surface 37 of the screen frame. Like the first embodiment of my invention, by turning the handle 35 the fastener 27 is rotatably engaged between the slot 32 and the locking screw 38, drawing the screen into tight engagement with its window frame seat. By screwing the head of each screw 38 against the engaged wall 31, the fastener is secured against accidental disengagement.

As disclosed in the drawings, four fasteners are used, a pair on each side. Depending upon the size of the removable sash to be secured within a window frame, any number of fasteners, preferably in pairs, may be used on opposite sides or the top and bottom of the removable sash frame.

It will be apparent that the construction of my improved screen or window fastener is very simple and devoid of any complicated arrangements which might get out of order. Moreover, the arrangement may be fitted with any type of removable sash which requires locking means for retaining them within a window frame.

It will, of course, be understood that numerous details of construction may be varied through a wide range without departing from the principles of this invention, and it is, therefore, not the purpose to limit the patent granted hereon otherwise than is necessitated by the scope of the appended claim.

I claim as my invention:

A lever device for securing a removable sash to a window frame having a headed locking pin projecting therefrom comprising, a metal stamping having a flat circular base, said base having a central aperture therethrough adapted for association with a fixed pivot on the removable sash, a lever handle extending upwardly and away from said base with its transverse axis parallel thereto, and a curved integral wall spaced from said handle and extending partially around and upwardly from the periphery of said base, said wall having a slot extending partially along its length and whose parallel edges are in spaced relation to said base, the blind end of said slot being closer to said base than its open end, the edges of said slot being adapted to receive therebetween and cam against the headed locking pin in the window frame as the device is turned by said handle.

ALBERT C. DOHRMAN.
